UNITED STATES PATENT OFFICE.

FREDERICK SYMONS, OF BURWOOD, NEAR SYDNEY, NEW SOUTH WALES,
AUSTRALIA.

CUSHION FOR HORSESHOES.

SPECIFICATION forming part of Letters Patent No. 772,685, dated October 18, 1904.

Application filed November 26, 1902. Serial No. 132,889. (No model.)

To all whom it may concern:

Be it known that I, FREDERICK SYMONS, farrier, a subject of the King of Great Britain, residing at Albert street and Parramatta Road, 5 Burwood, near Sydney, in the State of New South Wales and Commonwealth of Australia, have invented a new and useful Improved Cushion for Horseshoes, of which the following is a specification.

10 This invention relates to an improved cushion of resilient material, such as india-rubber or the like, to be inserted between the ordinary iron or steel horseshoe and the hoof of the horse.

15 This improved cushion for horseshoes is kept in position at the heel by taking against angles or rabbets on the edge of a heel bar or pad and at the toe by the ordinary horseshoe-nails, which after passing through the 20 shoe also pass through the cushion into the hoof. This improved cushion is peculiar in that it has a comparatively thick pad or bar joining the two ends or heel of the shoe-shaped cushion and in that it tapers in thickness from 25 heel to toe in the part or body which is inserted above the shoe on the hoof. This improved cushion has a further peculiarity, which is beneficial but not indispensable, in that it has an upper lining or surface to take against the 30 hoof, made of wire-gauze or the like, integral with the body and molded or placed on the body during manufacture. If desired, also the cushion may have a web holding the peripheral part or body together, which web 35 may sometimes be cut away to expose the frog and at other times may be formed as a reverse hood to take over the frog.

In order that this invention may be clearly understood, reference will now be made to the 40 drawings herewith, in which—

Figure 1 is a plan of the lower or ground face (with the shoe removed) of a horseshoe-cushion constructed according to this invention. Fig. 2 is a view of the upper or hoof face of the same cushion. Fig. 3 is a similar view to Fig. 1 of a modified construction of improved horseshoe-cushion having a larger heel-pad. Fig. 4 is a central sectional view 45 on line 4-4, Figs. 1 and 2, of the improved

cushion and the horseshoe. Fig. 5 is a similar 50 sectional view on line 5-5 in Fig. 3. Fig. 6 is an edge view of the cushion of Fig. 3 and its horseshoe. Figs. 7, 8, and 9 are sectional views of the cushion and the shoe, taken on the lines bearing these respective numbers in 55 Fig. 1; and Figs. 10, 11, and 12 are similar views on similarly-numbered lines in Fig. 3.

This improved cushion for horseshoes is made or molded of india-rubber vulcanized or otherwise treated or of similar resilient, 60 springy, or elastic material. It has a peripheral body 13 approximating to the horseshoe shape and tapering in thickness from the heel to the center of the toe, where the material is as thin as may be. During the manufacture or molding there is placed on the upper or hoof face a lining or facing 14, of wire-gauze or similar material. Across the space between the two ends of this body is a heel 65 bar or pad 15, with a diamond or cross corrugated or roughened face 16, adapted to protrude below the ground-face of the shoe 17. The outer end edges of this bar or pad 15 70 form angles or rabbets, against which the inner edges of the body of the shoe 17, shaped for this purpose, take or grasp, and thus hold the back of the cushion in place. This bar is also, preferably, curved or arched downward upon its upper side, so that pressure of impact upon the road will not to its full extent 75 be transmitted directly to the central portion of the frog, but will be at least partially distributed to the heels.

In use a horse is shod as ordinarily, the improved cushions being placed after the shoe 80 is fitted below the hoof and above the shoe, and the ordinary nails are then driven through shoe and cushion, which is then trimmed and finished neatly with the hoof.

It will be found that a horse shod with these 85 cushions is very much easier in its motions and actions and the shocks of the actions are minimized. Also the shoes will last longer than ordinarily and the horse will have a firmer and non-slipping grip upon the surface 90 of the roadways, whether of wood blocks or otherwise. The wire-gauze facing 14 not only protects the material of the cushion from de-

structive exudations from the hoof and from gatherings between the cushion and the hoof picked up from the roadways, but also gives the effect of a firm grip to the hoof itself.

5 Having now particularly described and ascertained the nature of my said invention and in what manner the same is to be performed, I declare that what I claim is—

A horseshoe-cushion of rubber tapering from its heel toward its toe, of substantially horseshoe shape, having a wire-gauze of similar shape molded into its upper surface and an integral bar connecting the heel portions

of the cushion, the ends of said bar extending short of the marginal portion of the cushion 15 and being rabbeted, and said connecting-bar having a substantially central depression in its upper surface, the lower surface thereof being roughened.

In testimony whereof I have signed my name 20 to this specification in the presence of two subscribing witnesses.

FREDERICK SYMONS.
